UNITED STATES PATENT OFFICE.

CLARENCE O. McCALL, OF BROOKFIELD, ILLINOIS.

PACKING-SUPPORTING DEVICE.

Application filed June 19, 1926. Serial No. 117,023.

My invention relates to improvements in journal box packing supports.

The principal object of the invention is to provide an improved packing supporting device adapted to maintain the packing in contact with the journal to be lubricated, and which admits of the packing of the journal in substantially the same manner and with the same tools as are employed in packing conventional boxes at the present time, the said improvements contemplating the use of substantially less packing per box than is used at the present time but without alteration of the box construction.

15 A further object is to provide a packing supporting device which will permit the packing to rest upon the floor of the box to absorb the free oil therein, and which will prevent the packing from being carried by 20 the journal upwardly under the brass by the rotating journal, or moving longitudinally of the box out of the packing space.

Another object is to provide a device comprising a pair of complementary members 25 adapted to be inserted in a journal box through a door thereof, one on each side of the journal, and being resiliently connected at their lower edges and having resilient contact with the side walls of the journal 30 box which will hold the packing against the journal, even when the same is subjected to the hammering incident to passage of the car over rough tracks, such as crossings, frogs and low joints and vibration caused by 35 the ground being frozen, and which will prevent the packing from settling away from the journal during a period of non-use, thereby obviating the necessity for lifting and loosening the packing as is the necessary general practice at the present time.

40 A further object is to provide a packing supporting device which may be provided with a gate, or the like, as an additional means for preventing the packing from 45 moving longitudinally of the box toward the door thereof and out of the packing space.

Other objects relate to various features of construction and arrangement of parts 50 which will become apparent from a consideration of the following specification and accompanying claims, wherein—

55 Figure 1 is a longitudinal sectional view of a conventional journal box showing a form of my improved packing supporting device therein.

Fig. 2 is a vertical sectional view taken on line 2—2, Fig. 1.

Fig. 3 is a broken longitudinal sectional view of a journal box showing a modified 60 form of my device therein.

Fig. 4 is a vertical sectional view taken on line 4—4, Fig. 3.

Fig. 5 is a detached elevation showing a further modification of my improvements. 65

Fig. 6 is a broken plan view illustrating the upper spring arrangement.

In the drawings, the conventional journal box 10 is provided with a lid or door 11, a journal 12 being enclosed in the box, which 70 journal is provided with the usual collar 13. A brass 14 rests upon the journal as illustrated.

At the present time, it is the general practice to insert packing, such as oiled waste 75 through the opening in the box, into the space beneath the journal, filling the lower portion of the box up to a level, approximately half way up on the journal. The packing is forced into the box in such quantity as to fill the lower portion of the box 80 and to contact with the lower portion of the journal.

After a period of use the packing tends to settle away from the journal and necessitates lifting or stirring up the waste in order that the journal will be properly lubricated. It also quite frequently happens that strands of the waste or packing are carried upwardly by the rotating journal 90 under the brass 14, which often is the cause of hot boxes. In addition to overcoming the above disadvantages of the present practice, my improvements contemplate also the use of considerably less waste than is required in packing the boxes in accordance 95 with the present practice.

In Figs. 1 and 2 are shown a pair of complementary packing supporting members 15 formed of sheet metal. The metal is resilient enough to flex sufficiently to permit the same to be inserted in position through the door of the box, and, when deflected to the full line position, shown in Fig. 2, from the dotted line position, by the pressure of the 105 packing 16, to exert pressure on said packing and hold the same in contact with the journal. The members 15 extend from the rear of the journal box to the forward side thereof. The forward ends 15^a of members 15 thus extend somewhat beyond the end 110 of the journal 12 and serve as guides for

directing the packing into the space between said members and between the journal and the floor of the box. The members 15 are flexibly connected adjacent their lower edges by means of springs 17, two of which are shown in the drawings, although more may be employed, if desirable. The upper portions of the members 15 are slit to form the resilient straps or springs 18 which are bent outwardly to contact with the side walls of the journal box, and which tend to move said members pivotally about their lower edges toward the journal.

The device as thus constructed can be inserted in the journal box through the door thereof to the position shown in Figs. 1 and 2, it being necessary merely to flex the members slightly in passing the same around the collar 13 of the journal 12. The packing 16 is then inserted by means of an ordinary packing tool, between the members 15 with sufficient pressure to cause the said members to spring outwardly slightly, as indicated by the full line position in Fig. 2. By means of the flexible connections at the lower edges of the members 15, which give sufficiently to permit the members to be inserted in a standard box through the door thereof and the resilient contact with the wall of the box, the members exert a pressure on the packing which holds the same against the journal even under severe conditions of travel, as well as during periods of non-use. It is therefore unnecessary in the use of my improvements to raise the packing frequently as is the practice at the present time. It will also be seen that the packing 16 is adapted to rest upon the floor of the box whereby it can absorb any free oil which may be present. It will be noted that the arrangement and proportions of my improvements are such that the members 15 exert the greatest pressure on the packing adjacent the upper portion of the latter, which preferably terminates in a plane lower than the horizontal center of the journal. The effect of this construction is that the journal is less likely to carry strands of packing upwardly under the brass to cause the trouble referred to above, as any tendency of the packing to move with the journal is resisted by the relatively constricted passages between members 15 and the journal. To further assist in the gripping of the packing by the support, and to prevent the grabbing action of the journal, a number of openings 19 are provided in the members 15.

In the form of invention shown in Fig. 3, the packing supports 20 are formed of woven wire, which is preferably a resilient steel wire having sufficient resilience to recover its shape after deflection but flexible enough to permit the same to be passed around the collar 13 of the journal 12. In this form,

the lower edges of the supports are connected by coil springs 17, as in the above described modification, and they are also provided with springs 21 adjacent their upper edges. These springs are suitably secured to the members 20 by any approved means as being interwoven with the mesh of said members and having their ends bent outwardly, as shown in Fig. 4, to contact with the inner walls of the box 10. The device functions similarly to the above described modification, the reticulated construction serving to provide sufficient contact with the packing to prevent the same from being grabbed and moved upwardly out of position by the rotating journal, and the guide portion 20^a assisting in directing the packing into the packing space.

In Fig. 5, I have shown a further modification of my supporting device formed of sheet metal and having the general shape of the member 15, shown in Fig. 1. Instead of being provided with openings 19 of Fig. 1, the support 22 is provided with depressed portions or corrugations 23, which are arranged in staggered relation and serve to prevent the packing from being carried upwardly under the brass of the journal and to prevent any other displacement of the packing. The support 22 is slit to form upper springs 24. The lower edges of the members 22 are also connected by springs 17 as in the previously described modifications. Guide portions 22^a are also provided.

It frequently occurs, due to some action of the journal (probably the lateral movement of the same), or to the improper packing of the box, that the waste or packing material will tend to creep or move toward the door of the box and frequently actually flows through the door, causing loss of oil and permitting the entrance of dust and other foreign particles, as well as permitting the packing to drop from contact with the lower portion of the journal. It will be apparent that all forms of supporting members described above will tend to prevent the longitudinal movement of the waste toward the box door, due to the reticulated construction, the openings therein, or the corrugations of the different forms. I contemplate also the use of a gate 25, when desired, with each of the above described forms of packing supports, which gate is adapted to be hinged, as at 26, or otherwise suitably secured to one of the packing supporting members and to have a removable latch connection with the opposite member.

With the form of invention shown in Fig. 1, a suitable opening 28 may be made in one of the members 15 to receive the bent over free end 27 of gate 25, while in the form shown in Fig. 3 the end 27 can be passed through the mesh of said member, as will

be clear. An opening 28 may also be formed in the supporting member 22, shown in Fig. 5, for receiving the latch member 27. The member 25 is shown as being formed integral with the member 27 and as comprising merely a turn or two of wire, which permits the gate to be extended to different lengths in accordance with variations in the quantity of packing used, as will be obvious.

10 As shown in Fig. 1, for instance, the gate 25 is positioned a short distance to the left of the collar 13, as viewed in said figure, thus permitting the packing to lubricate the collar 13 which is desirable in case of an overriding brass, but serving to hold the packing against movement toward the box opening.

Although I have shown certain features of my improvements for the purpose of illustration, it will be apparent that various changes may be made therein without departing from the spirit of the invention as defined in the following claims.

What I claim is:

25 1. Journal box packing supporting means comprising a pair of members resiliently connected adjacent their lower edges and having springs at their upper edges for

urging said members in a direction to hold the packing against the lower portion of the 30 journal, said supporting members having their inner surfaces formed to resist displacement of portions of said packing by the rotating journal, and means extending transversely between said members for preventing the movement of said packing longitudinally of said box toward the door thereof.

2. Journal box packing supporting means comprising a pair of members resiliently 40 connected adjacent their lower edges and having springs at their upper edges for urging said members in a direction to hold the packing against the lower portion of the journal, said supporting members having 45 their inner surfaces formed to resist displacement of portions of said packing by the rotating journal, and means extending transversely between said members for preventing the movement of said packing longitudinally of said box toward the door thereof, said last named means comprising a gate secured to each of said members.

In testimony whereof, I have subscribed my name.

CLARENCE O. McCALL.
